US00D581155S

(12) **United States Design Patent**
Richardson et al.

(10) **Patent No.:** **US D581,155 S**
(45) **Date of Patent:** **** Nov. 25, 2008**

(54) **CASE**

(75) Inventors: **Curtis R. Richardson**, Fort Collins, CO (US); **Jason M. Thompson**, Broomfield, CO (US); **Matthew M. Glanzer**, Loveland, CO (US); **Jamie Lee Johnson**, Fort Collins, CO (US); **Alan V. Morine**, Fort Collins, CO (US)

(73) Assignee: **Otter Products, LLC**, Fort Collins, CO (US)

(**) Term: **14 Years**

(21) Appl. No.: **29/298,580**

(22) Filed: **Dec. 7, 2007**

(51) LOC (8) Cl. **03-01**

(52) U.S. Cl. **D3/218**

(58) **Field of Classification Search** D3/218, D3/201, 215, 226, 269, 272-273; 206/305, 206/320; 455/90, 92, 42; 379/455; 224/901, 224/904, 682-683, 666; D14/496, 156, 138

U.S. Appl. No. 29/284,532, filed Sep. 10, 2007.

Primary Examiner—Catherine R Oliver*Attorney, Agent, or Firm*—William W. Cochran; Cochran Freund & Young LLC

(57)

CLAIM

The ornamental design for a case, as shown and described.

DESCRIPTION

FIG. 1 is an isometric view of a case showing our new design.

FIG. 2 is a front view thereof.

FIG. 3 is a top view thereof.

FIG. 4 is a left side view thereof.

FIG. 5 is a right side view thereof.

FIG. 6 is a bottom view thereof; and,

FIG. 7 is a rear view thereof.

The broken line showing of environment in the drawings is included for the purpose of illustrating only and forms no part of the claimed design.

1 Claim, 4 Drawing Sheets
